UNITED STATES PATENT OFFICE.

LAWRENCE L. STEINKE, OF FARMINGTON, ILLINOIS.

BARREL-CART.

1,374,406.

Specification of Letters Patent. Patented Apr. 12, 1921.

Application filed August 16, 1919. Serial No. 317,970.

To all whom it may concern:

Be it known that I, LAWRENCE L. STEINKE, citizen of the United States, residing at Farmington, in the county of Peoria and 5 State of Illinois, have invented certain new and useful Improvements in Barrel-Carts; and I do hereby declare that the following is a full, clear, and exact description of the invention, which will enable others skilled in 10 the art to which it appertains to make and use the same.

This invention relates to a can or barrel cart. One of the objects of the invention is to provide a structure in a cart of the character named, that will be simple in construction, thoroughly rigid, very convenient, and easy to operate.

Another object is to provide a cart that can be readily accommodated to barrels or 20 cans of any size.

Still another object is to furnish and provide a simple, easily manipulated means for tipping the cans or barrels to their dispensing positions.

To the end that my invention may be understood, I have provided the accompanying drawings wherein

Figure 1 is a plan of the cart,

Fig. 2 is a side elevation of the same with 30 the rear wheel removed, and

Fig. 3 is a front elevation of portions of the cans or barrels showing a casting clamped to one of them, which includes a trunnion to be supported in one of the supporting wheels.

Fig. 4 is a plan of a portion of the cart frame showing a modification of the structure arranged to carry a single can, barrel or other receptacle, and produced on a much 40 smaller scale than the other figures.

Fig. 5 is a plan of part of a barrel or other receptacle, showing a modified form of clamping rod, on a smaller scale. This figure also being produced on a much smaller scale.

Besides these objects, the invention relates to certain details of construction, to be pointed out herein, it being understood that I may vary the structure without departing from the spirit and intent of the invention.

As a represent, in this instance, a pair of

cans or barrels to be accommodated, B B representing castings, one of which is clamped to each can or barrel at its outer side, and each having an extended trunnion C for the ground wheel D. Said casting includes at each end a pair of spaced ears E notched to receive pair of rods F, having adjusting nuts G to engage the ears as shown. Between the cans or barrels is a pair of spacing blocks H, one of which is shown in Fig. 1, both being indicated by dotted lines in Fig. 2. These blocks are formed to fit the walls of the cans or barrels into them, and serve to space the latter apart. The castings B are of such a length 55 that the pairs of rods F will be spaced a sufficient distance from one another to bring them near enough to the ends of the barrels to firmly clamp the latter. By taking up the nuts G, the barrels will be rigidly 60 clamped with the blocks between them, the whole constituting a unitary structure, ready to receive the described carrying wheels D.

The frame of the cart may be constructed in any suitable or desired form. In the drawings, however, this comprises parallel side members J to each of which is attached, at its rear end, a casting K bored to pass over the described trunnion C, Fig. 3. The forward portions of the members converge, 75 by preference merely, and are then brought together into parallel extensions L, to constitute a reach or tongue, between which is pivoted a leg M, adapted to support the reach, but which may be folded, the dotted 80 line position, Fig. 2, when the cart is to be transported.

It may be here stated that the cart is peculiarly adapted for use in connection with gas engine outfits in field operation, 90 as in plowing, threshing and the like, the cans or barrels A holding the gasoline and lubricating oil, the reach or tongue being attached to the tractor or other implement for drawing the cart to the place for operations, the leg M being dropped as in Fig. 2 95 to support the tongue, when the field is reached.

As a convenience, a platform N is suspended from the frame in any suitable man- 100

ner, to receive cans or other containers, for carrying water to be supplied to the engine-radiator or for other purposes.

The cans or barrels A are furnished with 5 filling caps N' and faucets O and the contents of said cans or barrels may be dispensed at will by a convenient lever arrangement. The latter comprises a notched sector P as part of one of the described castings K, on the end of one of the frame portions J, Fig. 2, and a lever P' secured relatively to an adjacent casting B, so that in swinging said lever the last named casting will swing therewith as shown by 10 dotted lines in said Fig. 2.

The lever carries a guide block Q in which any usual spring held detent R, is slidable, the latter engaging any one of the notches of 15 said sector, as will be clearly understood, there being the usual latch S on the lever for actuating said detent.

When dispensing the contents of the barrels, the lever and latch when grasped to disengage the detent, will tilt the barrels 20 which trunnions C will roll or rock in the castings K and in the wheel hubs as is 25 obvious.

It is to be particularly observed that the 30 castings B are in no way attached to the barrels, but are merely clamped thereto by the barrel-embracing rods. For this reason cans or barrels of any size may be accommodated within the limits of spread of the main frame, smaller ones being accommodated 35 by the insertion between them of blocks of larger size than blocks H, in order to obtain a spread sufficient to, of necessity, position the said castings B where shown in Fig. 1.

40 Particularly in this respect do I believe my structure to be new in the art, since it is unnecessary to "take down" all of the parts of the cart to accommodate various sizes of the receptacles. By a suitable spacing member, also, such as T T, Fig. 4, one receptacle may be accommodated.

Though the rods E, constituting bands, are separate portions engaging at their ends the castings B, they may be otherwise constructed and still serve the purpose for 50 which they are designed. As another manner of securing the cans or barrels, or even a single one, the pairs of rods may be replaced by a single one U as shown in Fig. 5, though the double rods are preferable, since more conveniently handled and more easily attached.

Since the lever P' is not attached in any way to either receptacle, both may be released by loosening the rods E and others substituted, the lever tilting them through the castings of which said lever, in effect, is a part.

I am not aware of a structure in a cart 60 employing a plurality of barrels wherein

said barrels themselves act, together with a clamping means and trunnions, as the sole support of the whole between the wheels, or as taking the place of an axle or supporting framing extending from wheel to wheel. 70 Such a structure not only makes a cart that can be built at much lower cost than otherwise, but gives an implement much lighter in weight and one that can be set up in a much shorter time than others because of 75 the few parts entering into its construction. The framing, the rods FF and the barrels constitute the only parts to be assembled. The barrels practically act as an axle.

Not only can the assembling take place 80 quickly, but the cart can be readily set up and taken down even by an inexperienced person and barrels substituted for those in use.

I claim—

1. In a barrel cart, the combination of a plurality of barrels, means embracing both barrels acting to clamp them in rigid relation, a spacing member clamped between the barrels by said embracing means, trunnions 90 extending from the embracing means at opposite sides thereof, supporting wheels engaging the trunnions, and a draft frame engaging the trunnions.

2. In a barrel cart, a barrel, a wheeled 95 supporting structure upon which the barrel is pivotally mounted, a sector, and a lever to engage said sector, each of the latter being separately mounted upon and secured to one of the described parts.

3. In a barrel cart, the combination of a plurality of barrels to be supported, means embracing the barrels to clamp them in rigid relation including trunnions extending from opposite sides of the structure, wheels 105 to receive the trunnions, a draft frame connected to a part of the structure, and a tilting-lever fixed with respect to the barrels including a latch mechanism adapted for fixing the barrels in adjusted positions, 110 and a part on the framing to receive the said mechanism.

4. The combination with a frame and a pair of wheels, of a plurality of barrels, means to clamp said barrels together in rigid 115 relation including a member secured by said means at the outer side of each barrel structure, each of said members including a trunnion adapted to engage the frame and one of the wheels, a tilting-lever fixed with respect to the barrels including latch mechanism, and a sector fixed with respect to the frame.

5. In a barrel cart, a barrel structure, a member lying at each of two opposite sides 125 thereof, each including a trunnion, means to clamp the members upon said structure, wheels for receiving the supporting trunnions, a draft device engaging the trunnions, a lever fixed with respect to the struc- 130

ture including a latch, and a sector fixed with respect to the draft device to receive said latch.

6. In a can or barrel cart, the combination with a main frame and wheels, and a barrel to be supported thereon, of a member detachably secured relatively to the barrel, a tilting lever secured thereto, including a

latch, and a sector secured relatively to the main frame to receive said latch. 10

In testimony whereof I affix my signature, in presence of two witnesses.

LAWRENCE L. STEINKE.
